UNITED STATES PATENT OFFICE.

WILLIAM HENRY JONES, OF RUPERT, IDAHO.

LEVELING-ROD.

No. 894,955.

Specification of Letters Patent.

Patented Aug. 4, 1908.

Application filed October 10, 1907. Serial No. 396,820.

To all whom it may concern:

Be it known that I, WILLIAM HENRY JONES, a citizen of the United States, residing at Rupert, in the county of Lincoln and State of Idaho, have invented certain new and useful Improvements in Leveling-Rods, of which the following is a specification, reference being had to the accompanying drawings.

My invention relates to improvements in leveling rods and more particularly to one which is self computing and especially adapted for the use of farmers and irrigators in laying out ditches and drains and doing all engineering connected with an irrigated farm.

The principal object of the invention is to provide a rod of this character which may be used by persons of little experience in engineering work.

Another object of the invention is to provide a leveling rod which may be conveniently adjusted for any size ditch and which will give cuts or fills for both banks and bottom at the one reading, so as to dispense with the necessity of figuring.

Another object of the invention is to provide an attachment for a leveling rod by means of which a ditch may be readily cross sectioned.

With the above and other objects in view, the invention consists of the novel features of construction and the combination and arrangement of parts hereinafter described and claimed, and illustrated in the accompanying drawings, in which

Figure 1 is a front elevation of my improved leveling rod; Fig. 2 is a side elevation of the same; Fig. 3 is a rear elevation; Figs. 4, 5, and 6 are transverse sectional views taken respectively on the planes indicated by the lines 4—4, 5—5 and 6—6 in Fig. 1; and Fig. 7 is a detail longitudinal section taken on the plane indicated by the line 7—7 in Fig. 3.

My improved leveling rod comprises a rear or lower section 1 and a front or upper section 2, which latter is adapted to slide upon the former and to be adjustably secured thereto by means of a set screw 3 or an equivalent clamping device arranged preferably at the upper end of the rear section or rod as more clearly shown in Fig. 4. In the sides of the front section or rod 2 are formed longitudinal grooves 4 to receive flanges 5 formed on plates 6 secured to the opposite sides of the rod 1 for the purpose of holding the two rods or sections together in sliding engagement.

At the lower end of the rod 2 is secured a U-shaped strap 7 which surrounds and slidably engages the rod 1 for a similar purpose. The downward sliding movement of the rod 2 upon the rod 1 is limited by a stop 8 preferably in the form of an angle bracket secured upon the front face of the rod 1 adjacent to its lower end as clearly shown in the drawings. The front rod is graduated upon its front face in feet and tenths of feet from a zero point adjacent to its center which point is marked 0, to its upper and lower ends as clearly shown in Fig. 1, the graduation 8 upon the upper portion of said rod being arranged upon the left hand side of a centrally disposed longitudinal line 9 and the corresponding graduations 10 on the lower portion of said rod being arranged upon the right hand side of said line. The rear face of the front rod is graduated in feet and tenths of feet as shown at 11 from its top to its bottom and the corresponding face of the rear rod is similarly graduated as shown at 12 from its bottom to its top.

13 denotes the target which is slidably mounted upon the front rod 2 and is adapted to be secured in an adjusted position thereon by a set screw or equivalent clamping device 14. This set screw is arranged in the center of the lower portion of the target and has its inner end bearing against a resilient metal shield or guard plate 15 secured upon the back face of the target for the purpose of protecting the rod 2 from being scratched or marred by the set screw. Said target is in the form of a circular plate having a centrally disposed vertical opening 16 to expose the front face of the rod 2 and side plates or flanges 17 which engage the opposite sides of said rod 2 and are formed with ribs 18 which enter and slide in the grooves 4 in said rod as more clearly shown in Fig. 5. The front face of the target is provided with vertical and horizontal intersecting lines, the vertical one of which registers with the vertical line 9 upon the front rod and the horizontal one is adapted to coact with the graduations 8, 10 on said rod as hereinafter explained. The said intersecting lines on the front face of the target divides it into quarters, the two opposite ones of which are preferably colored and in the others are printed "Fill" and "Cut" as clearly shown in Fig. 1.

To enable a ditch to be cross sectioned I provide an attachment in the form of a supplemental rod 19 which is slidably adjustable

on the target and arranged upon the right hand side of the front rod 2. I also provide upon the right hand side of the upper portion of the front face of the rod 2 graduations 24 which co-act with said rod as presently explained. Said rod 19 is graduated in feet as at 20 from its top to its bottom and it is slideable in a guide sleeve 21 arranged upon the rear face of the target. A set screw or equivalent clamping device 22 is provided in the sleeve for securing the rod 19 in an adjusted position. The graduations 20 on the front face of said rod 19 are exposed upon the front face of the target in a small opening 25 formed in it on one side of the opening 16. If in cross sectioning a ditch, the land over which the ditch is to be constructed is on the side of a hill, or very uneven, the rod may be placed at each of the side stakes, the target 20 made to aline with the level, and the reading at the top of the small rod 19 will be the exact cut or fill for that point.

The numerous uses to which the device can be put will be readily understood from the foregoing description by one familiar with the devices of this character, but I will describe in detail a few of the uses of the same. When it is desired to level a field, the attachment or rod 19 may be removed by 25 loosening the set screw 22 and sliding it out of its sleeve or guide 21. The target is then set at zero and the lower end of the device is placed upon a stake which is driven at a suitable point. The level having been conveniently located, the set screw 3 is loosened and the front rod 2 is slid up or down until the target is in line with the level. Said set screw is then tightened to clamp the front rod upon the rear one. The stake is then 30 marked any elevation, say for instance 20 feet. The rod is then moved to the next stake or station and the set screw 14 is loosened to allow the target to be slid up or down until in line with the level. All readings below 0 are added to the original elevation and all above are subtracted from it and the result is marked on the stake. When it is desired to move the level, the rod is set at 35 the last convenient station, the target is set 40 at 0 and then alined with the level as above explained. Then continue as before, adding or subtracting from the elevation given on last stake.

When it is desired to cross section a ditch, say for instance a ditch 2 feet from bottom to top of the bank with a grade of .1 of a foot to 100 feet, set target at 0 and adjust the rod 19 until its upper end marked 0 is 2 feet above the center of the target. Then select a place 45 from which it is desired to start the ditch and determine what cut or fill is necessary to the bottom of the ditch. For instance, say a cut of 1.5 feet is required, set target to read cut 1.5 feet and then set level at any convenient place. Raise or lower front rod to aline with

level, then step off 100 feet to next station. Raise front rod .1 foot for the grade, then move target to aline with level. The figures appearing at the center line of target on front rod are marked on center stake for the bottom of the ditch. The figures or graduations 20 on the rod 19 appearing in the opening 25 in the target and those on the right hand side of the upper portion of the rod 2 opposite the upper or 0 end of the rod 19 are 50 added and their sum is the distance from center stake at which to drive each side stake. The figures on the left hand side of the upper portion of the rod 2 opposite the upper or 0 end of the rod 19 are marked on each side 55 stake. When it is desired to move level, set target to read same as center stake at last station then raise or lower front rod until target is in line with level, and proceed as before.

Having thus described my invention what I claim is:

1. A leveling rod comprising front and rear sections slidably engaged and adjustably connected, graduations upon the front rod 90 extending from zero point adjacent to its center to its opposite ends and a target slidably and adjustably mounted upon the front rod, substantially as and for the purpose set forth.

2. A leveling rod comprising front and rear sections slidably engaged and adjustably connected, graduations upon the front face of the front section from zero point adjacent to its center to its opposite ends, graduations upon another face of the front section extending from its top to its bottom, graduations upon one face of the rear section extending from its bottom to its top and a target slidably and adjustably mounted upon the front section, substantially as and for the purpose set forth.

3. A leveling rod comprising front and rear sections slidably connected, a set screw for clamping the front section in an adjusted position upon the rear one, graduations upon the front face of the front section from zero point adjacent to its center to the opposite ends of said section, a target slideable upon the front section and a set screw carried by the target for clamping it in an adjusted position, substantially as and for the purpose set forth.

4. A leveling rod comprising front and rear sections, the front section having longitudinal grooves in its side edges, graduations upon the front rod extending from zero point adjacent to its center to its opposite ends, plates upon the opposite sides of the rear section formed with flanges or tongues to engage said grooves, a strap surrounding the rear section and secured to the lower portion of the front section, a stop upon the rear section to limit the downward movement of the front section, a set-screw arranged in the rear 120 125 130

section and adapted to impinge against the front section to hold it in an adjusted position, and a target slidably and adjustably mounted upon the front section.

5 5. A leveling rod comprising front and rear sections, the front section having longitudinal grooves in its side edges, graduations upon the front rod extending from zero point adjacent to its center to its opposite ends, 10 plates upon the opposite sides of the rear section formed with flanges or tongues to engage said grooves, a strap surrounding the rear section and secured to the lower portion of the front section, a stop upon the rear section 15 to limit the downward movement of the front section, a set screw arranged in the rear section and adapted to impinge against the front section to hold it in an adjusted position, a target having side flanges formed with 20 tongues to engage the grooves in said front section, and a set screw in said target to engage the front section and hold the target in an adjusted position thereon.

6. A leveling rod comprising slidably and 25 adjustably connected front and rear sections, the graduations 8, 10 upon the front face of the front section extending from zero point arranged adjacent to the center of said sec-

tion to the opposite ends of the latter, the 30 graduations 24 upon the upper portion of said front section, a target slidably and adjustably mounted upon the front section and the graduated rod 19 slidably and adjustably mounted upon the target, substantially as 35 and for the purpose set forth.

7. A leveling rod comprising slidably and adjustably connected front and rear sections, the graduations 8, 10 upon the front face of the front section extending from zero point 40 arranged adjacent to the center of said section to the opposite ends of the latter, the graduations 24 upon the upper portion of 45 said front section, a target provided with a central opening to expose the graduations upon the front section, a second opening to one side of the central one, a guide upon the rear face of the target, the graduated rod 19 50 slideable in said guide and a clamping device for securing said rod 19 in the guide, substantially as and for the purpose set forth.

In testimony whereof I hereunto affix my signature in the presence of two witnesses.

WILLIAM HENRY JONES.
